UNITED STATES PATENT OFFICE.

MADISON D. SHIPMAN, OF DE KALB, ILLINOIS.

DESIGN FOR A TOP FOR SOCKET MEMBERS FOR GLOVE-FASTENERS:

SPECIFICATION forming part of Design No. 32,278, dated February 27, 1900.

Application filed June 23, 1899. Serial No. 721,986. Term of patent 14 years.

To all whom it may concern:

Be it known that I, MADISON D. SHIPMAN, a citizen of the United States, residing at De Kalb, in the county of De Kalb and State of Illinois, have invented and produced a new and original Design for the Top of the Socket Member of a Glove-Fastener; and I do hereby declare the following to be a full, clear, and exact description of the invention, such as will enable others skilled in the art to which it appertains to make and use the same.

In the drawings, Figure 1 is a top plan view of the top of a glove-fastener, showing my new design. Fig. 2 is a cross-section of the same on line X X of Fig. 1.

The design pertains to surface ornamentation of the top or shell of the socket member of a glove-fastener; and its essential feature consists of a group of correspondingly curved scrolls radiating from the center of the top or shell.

My design also includes grooves, depressions, or indentations in the top surface of the article, and, as shown in the drawings, the bottoms of said grooves, depressions, or indentations have the appearance of being crossed with numerous fine ridges.

In the drawings the reference-letter A designates the grooves forming the scrolls and radiating from a central circular depression a, said scrolls extending to within a short dis-

tance of the periphery of the shell and terminating within themselves in substantially circular enlargements a'. Double spurs or fins are outlined by branch grooves or depressions a" at the backs of the scrolls not far from said terminal enlargements, and single spurs or fins are outlined by branch grooves or depressions a" at the inner sides of the scrolls, near the outermost portions of the latter.

The reference-letter C designates substantially triangular depressions between the scrolls near the periphery of the shell, and the letter D substantially triangular depressions between the inner portions of the scrolls.

The design is made to stand out in relief by a series of fine cross-ridges in the grooves A and in the depressions C and D, as shown in Fig. 1 of the drawings.

Having thus fully described my invention, what I claim as new, and desire to secure by Letters Patent of the United States, is—

The design for the top of the socket member of a glove-fastener or similar article, substantially as shown and described.

In testimony whereof I affix my signature in presence of two witnesses.

MADISON D. SHIPMAN.
